(57) CLAIM

The ornamental design of a pen design, as shown and described.

DESCRIPTION

FIG. 1 is a perspective view of the front, left, and top side of a pen showing an embodiment of the new design.

FIG. 2 is a front view thereof.

FIG. 3 is a rear view thereof.

FIG. 4 is a right view thereof.

FIG. 5 is a left view thereof.

FIG. 6 is a top view thereof; and,

FIG. 7 is a bottom view thereof.

The broken lines show portions of the article that form no part of the claimed design.

1 Claim, 6 Drawing SheetsFIG. 1

FIG. 3

FIG. 2

FIG. 4

FIG. 5

FIG. 6

FIG. 7
